BOWLING ALLEY

Filed June 15, 1931

2 Sheets-Sheet 2

UNITED STATES PATENT OFFICE

HENRY K. HESS, OF WOLCOTT, NEW YORK

BOWLING ALLEY

Application filed June 15, 1931. Serial No. 544,555.

This invention relates to certain improvements in bowling alleys of the class set forth in my pending application Serial No. 489,982, filed October 20, 1930, in that it is of the self-service type having an outgoing runway and an underlying return runway for the balls, together with means for deflecting the balls from the distal end of the upper runway onto the return runway, and additional means for deflecting the balls from the proximal end of the return runway onto the pin-supporting table or platform for displacing the pins which may be stacked thereon.

The main object of the present invention is to increase the general efficiency and range of usefulness of the apparatus shown in my pending application, and at the same time to reduce to a minimum the vibration and noise incidental to the operation of the power-driven driving member for impelling the balls along the return runway by supporting the rotary impeller and motor upon bearings independently of the runways and their supports.

One of the specific objects is to make the apparatus in sectional lengthwise units so that the length of the runways may be increased or diminished according to the space available for the installation of said units or according to the wishes of those installing such apparatus.

In other words, I have sought to make the device in various sizes for installation in private houses and clubrooms, as well as in public halls.

Another object is to normally support the impeller in such manner that its lower face will be disposed a distance above the distal end of the return runway slightly less than the diameter of the ball to frictionally engage the latter and thereby to impel the same to the proximal end and return to the pin-supporting table with sufficient force to displace the pins, and at the same time to allow a limited vertical movement of the impeller against the action of compression springs to assure its contact with the upper face of the ball.

Another object is to provide the impeller with a resilient peripheral covering, prefer-

ably of rubber or rubber composition to increase its frictional contact with the ball, and thereby to further assure a positive return drive of said ball.

A further object is to arrange the players stand at the proximal end of the outgoing runway in longitudinally spaced relation thereto in substantially the same horizontal plane and also arrange the pin-supporting platform lengthwise of and across said space in a plane below the upper faces of the players stand and upper runway, but in vertically spaced relation to the lower runway to allow the balls to return thereunder.

Other objects and uses relating to specific parts of the invention will be brought out in the following description.

In the drawings:—

Figure 1 is a top plan of the bowling alley embodying the various features of my invention.

Figure 2 is a side elevation of the same.

Figures 3 and 4 are enlarged transverse vertical sectional views taken respectively in the planes of lines 3—3 and 4—4, Figure 1.

Figure 5 is an enlarged fragmentary longitudinal vertical sectional view, taken in the plane of line 5—5, Figure 1.

Figure 6 is an enlarged detail vertical sectional view taken in the plane of line 6—6, Figure 4.

Figure 7 is a detail vertical sectional view taken in the plane of line 7—7, Figure 6.

Figure 8 is an enlarged detail vertical sectional view taken in the plane of line 8—8, Figure 1, showing one of the pin-centering devices and a portion of the lower end of one of the pins, partly in section, in operative position on the pin-supporting platform.

Figure 9 is a diagrammatic view of the electric wiring system for controlling the operation of the pin-centering studs.

Figure 10 is a detail sectional view similar to Figure 8, showing a modified means for operating the pin-centering studs.

As illustrated, this apparatus comprises an upper outgoing runway 1 and a lower or underlying return runway 2, both of which are mounted in and upon a suitable supporting frame 3 and may be made of any suit-

able length and width depending somewhat upon the size of the room or hall in which it is installed; but in any case the combined length of both runways will be approximately equal to twice the length of the complete apparatus.

For example, when the apparatus is installed in public halls or other places for public use, the combined lengths and widths of both runways will be substantially equal to that commonly employed in such places.

The upper runway 1 is disposed in a substantially horizontal plane, while the lower runway 2 is arranged in vertically spaced relation to the upper runway and extends from the vertical plane of the distal end thereof some distance beyond the proximal end and is preferably slightly inclined downwardly from its distal end to its proximal end to assist in the return travel of the balls from the distal end to the proximal end of the apparatus.

A buffer block 4 forming a part of the main-supporting frame is extended across the distal ends of the runways 1 and 2 and is provided with a concave substantially semi-circular deflecting face 5 having its upper edge overlying the rear end of the upper runway 1 in vertically spaced relation thereto sufficient to allow the ball to pass through the intervening space.

The lower edge of the same deflecting surface is substantially co-incident with the upper surface of the distal end of the lower runway 2, said deflecting surface being spaced from the rear end of the upper runway 1 a distance sufficient to allow the ball to pass therethrough, as shown more clearly in Figure 5.

An additional buffer block 6 forming a part of the main supporting frame extends across the proximal end of the apparatus and is provided with a concave substantially semi-circular deflecting surface 7 having its lower edge substantially coincident with the upper surface of the proximal end of the lower runway 2 and its upper edge disposed in about the same horizontal plane as, but in longitudinally spaced relation to, the proximal end of the upper runway 1.

The distance between the lower and upper runways 1 and 2 is somewhat greater than the combined diameters of the balls —a— and impeller drum presently described, to afford ample space for the return of the ball, shown by dotted lines in Figure 5, along the lower runway 2 and below the impeller drum.

The bowling pins as —b—, shown by dotted lines in Figure 5, are adapted to be stacked in the usual manner upon a platform 8 which is mounted within and upon the frame 3 in a substantially horizontal plane lengthwise of and across the intervening space between the upper edge of the deflector block 6 and front end of the upper runway 1.

The platform 8 is disposed in vertically spaced relation to and above the underlying portion of the lower runway 2 a distance somewhat greater than the diameter of the ball —a— to allow free passage of the ball through the intervening space, said platform being also disposed in vertically spaced relation to and below the level of the upper runway 1 a distance corresponding approximately to the height of the bowling pins —b— when the latter are stacked in an upright position thereon, as shown by dotted lines in Figure 5.

The upper surface of the deflector block 6 constitutes what may be termed the players stand 6' which is disposed in substantially the same horizontal plane as the upper surface of the runway 1 so that the player on the stand 6' must throw the ball to the upper runway 1 and therefore across the intervening space between said runway and players stand, or rather across the upper surface of the platform 8 and upper ends of the bowling pins thereon.

It will be noted, however, that the length of this space is relatively short as compared with the length of the upper runway, or just sufficient to permit proper stacking of the bowling pins —b— upon the platform and within said space.

The purpose in arranging the platform 8 in a plane below the upper surface of and between the players stand 6' and proximal end of the upper runway is to enable the player to witness the effect of each play of the ball upon the pins while facing the distal end of the apparatus or in the direction of throw of the ball, and thereby to obviate the necessity of turning around to witness such plays as in my prior application, referred to.

The upper edge of the proximal deflector block 6 overhangs the adjacent end of the platform 8 in vertically spaced relation thereto somewhat greater than the diameter of the ball to allow the ball to pass therethrough when returned along the lower runway 2 and deflected upwardly and rearwardly by the deflecting surface 7.

It will be observed upon reference to Figure 5 that when the bowling pins —b— are stacked upon the platform 8, the upper ends will be disposed in a plane slightly below that of the upper surfaces of the players stand 6' and runway 1 so that the ball may be thrown across the intervening space without liability of hitting the upper ends of the bowling pins.

The distal end of the platform 8 extends some distance beyond the proximal end of the upper runway 1 and is provided with a buffer plate 9 for limiting the rearward movement of the bowling pins —b— when the latter are displaced from their stacked positions by the operation of the ball, in a manner hereinafter described, it being understood that the

space between the rear end of the platform 8 and overhanging portion of the upper runway 1 forms a pocket 9' for receiving the displaced bowling pins —b—.

5 An additional player's stand 10 is placed in operative position closely adjacent the front end of the stand 6' with its upper surface coincident therewith to form an extension thereof to enable the player to have ample space 10 for making the desired plays, said stand being provided at one side with a step or steps 11 to permit easy access thereto.

The main supporting frame 3, together 15 with the deflector blocks 4 and 6, and additional players stand 10, are adapted to be supported upon a level floor or other suitable support, not shown.

A storage shelf 12 is preferably secured to the outer side of the frame 3 adjacent the step 20 11 and corresponding side of the players stand 6' and is provided with a series of holes 13 for receiving and supporting the lower tapered ends of the bowling pins —b— when not in use.

25 Suitable power-driven means is provided for engaging and rolling the ball —a— along and upon the lower runway —2— from the distal end to the proximal end thereof with sufficient force to cause it to travel upwardly 30 along the deflecting surface 7 upon the platform 8 for displacing the bowling pins from their upright positions.

This means consists, in this instance, of a 35 rotary drum 14 mounted upon a shaft 15 and extended across the intervening space between the distal ends of the upper and lower runways, as shown more clearly in Figures 4 and 5.

40 This drum or impeller is disposed in such manner that its lower face will be normally spaced from the underlying upper face of the lower runway 2 a distance slightly less than the diameter of the ball —a—, so that when the latter is deflected from the rear end 45 of the upper runway onto the underlying end of the lower runway, the lower face of the periphery of the drum 14 will frictionally engage the upper face of the ball and thereby propel said ball with considerable force 50 forwardly along the lower runway and upwardly along the deflector surface 7 onto the proximal end of the platform 8 for displacing the pins.

55 The drum is preferably provided with a peripheral sleeve or covering 14' of relatively soft rubber or equivalent resilient material extending throughout the length thereof for increasing its friction with the surface of the ball and at the same time compensating 60 for any slight shortage of the distance between the lower face of the drum and upper face of the underlying portion of the lower runway.

65 The opposite ends of the shaft 15 of the drum 14 are extended through vertically

elongated openings 16 in the opposite upright side walls of the main frame 3 and are provided with sleeves 17 which are journaled in horizontally split bearings 18 having their lower sections 19 rigidly secured by 70 bolts 20 to suitable supporting standards 21, as shown more clearly in Figures 4, 6 and 7.

The upper bearing sections 19' are movable vertically relatively to the lower sections 19 and are guided in their vertical movement by 75 guide bolts 22 which are passed through registering apertures in the lower and upper bearing sections 19 and 19', as shown more clearly in Figure 6, and are provided at their lower ends with heads 22' engaging the undersides of the lower bearings 19, said bolts being extended upwardly some distance above the upper bearings 19' and are provided at their upper ends with adjustable nuts 23 in spaced relation to the upper bearing 80 sections.

The upwardly projecting ends of the bolts 22 are surrounded by compression springs 24 having their lower ends engaged with the upper bearings 19' and their upper ends engaged with the lower nuts 23 for exerting downward pressure upon the upper bearing 19' and at the same time permitting limited upward movement of the drum 14 and upper bearing 19' in case the drum should be slightly elevated by the impinging of its periphery with the ball —a— when the latter is passing thereunder, or during the return of the ball by the propeller along the lower runway 2. See Figure 6. 90

In other words the purpose of this relative vertical movement of the bearing member 19' with and against the action of the springs 24 is to cooperate with the resilient surface 14' of the drum in assuring frictional contact of the drum with the balls as the latter are deflected from the distal end of the upper runway onto the corresponding end of the lower runway and at the same time to compensate for slight variations in the diameter 110 of the balls —a—.

The drum or impeller 14 is adapted to be rotated in the direction indicated by arrow —x—, Figure 5, at a relatively high speed for propelling the ball —a— from the distal end 115 forwardly onto the platform 8 with sufficient force to displace the pins —b—.

For this latter purpose one end, preferably the right hand end, of the shaft 15 is provided with a pulley 25 connected by a belt 26 to another pulley 27 on the shaft of an electric motor 28, as shown more clearly in Figures 4 and 5. 120

The motor 28 is enclosed in a suitable housing 29 at the distal end of and closely adjacent the distal deflector block 4, said motor being provided with a supporting base 30 which may be bolted or otherwise secured directly to the floor upon which the frame 3 is mounted to avoid the transmission of any 125 130

vibrations of the motor to the supporting frame 3 for the runways 1 and 2, it being understood that under these conditions the belt 26, Figure 5, will pass through a suitable opening 29' in aligned portions of the deflector block 4, as shown more clearly in Figure 4.

It will be noted upon reference to Figures 1, 2 and 4 that the drum-supporting standards 21 are secured by bolts 31 or equivalent fastening means to the floor upon which the frame 3 is mounted, but independently of said frame so as to reduce to a minimum the transmission of vibrations or other movements of the drum to said frame, due to the fact that the openings 16 through which the bearing members 17 extend are sufficiently large to prevent contact of said bearing members with any part of the supporting frame 3.

The upper bearing members 19' are held against lateral displacement by guide-plates 32 which are secured by screws 33 or equivalent fastening means to the outer side faces 25 of said upper bearing member 19' to extend downwardly in over-lapping relation to the outer faces of the lower bearing members 19, the upper inner portions of the standards 21 being provided with recesses 34 in which the guide-plates 32 are movable as the drum 14 and bearing member 19' are moved vertically during the driving operation of the ball a. (See Figs. 4 and 7.)

The main frame 3 and runways 1 and 2 are 35 preferably divided at 35 intermediate their ends to form separate lengthwise sections and, if desired, they may be spaced longitudinally and another section interposed when it is desired to increase the length of the bowling alley, said sections being firmly clamped together end to end by clamping plates 36 which are secured to the outer faces of the upright side walls of the adjacent ends of the sections by bolts 37 or equivalent releasable 45 clamping means.

The upright side walls of the main frame 3 are provided with lower and upper rails 38 and 39 which are arranged in vertically spaced parallel relation to form an intervening space 40 extending nearly the full length of the upper runway 1 thus permitting access to the lower runway to remove any ball which may fail to return to the proximal end of the bowling alley.

For a similar purpose one of the upright side walls, in this instance the left hand side, is provided with a lengthwise opening 41 in a plane below the pin-supporting platform 8 and having its forward end enlarged at 41' 50 to permit the removal of the ball by hand in case the latter should fail to return to the proximal deflector block 6.

The lower and upper rails 38 and 39 project upwardly a limited distance above their respective runways 1 and 2 to prevent lateral

displacement of the played ball from said runways.

The front end of the player's stand 10 is provided with an upwardly projecting guard-rail 10' to reduce the liability of accident to 70 the player by stepping off from that end of the stand.

The upper bearing members 19' are provided with suitable oil ducts 44 leading from adjacent bearings 17 to suitable oil cups 45 as 75 shown more clearly in Figure 6.

Suitable means is provided for centering the bowling pins b in proper relation upon the supporting platform 8 and for this purpose the platform is provided with a plurality of, in this instance ten vertical openings 46, one for each of the bowling pins b for receiving a corresponding number of centering studs 47 which are adapted to enter sockets b' in the lower ends of the pins and, as shown in Figure 8, are automatically forced upwardly into said sockets by springs 48, but are adapted to be drawn downwardly by electro-magnets 49, the latter being incorporated in the platform 8. 90

Under this construction, however, it will be necessary to have the several magnets energized during the playing operation, which, of course, is of longer duration than the operation of restacking the pins upon the platform, and it would, therefore, be preferable to provide means whereby the centering studs will be moved to their operative positions only during the restacking operation, and in Fig. 10 I have shown a preferred construction for accomplishing the latter result. 100

Thus, in Fig. 10 I have shown each centering stud 47 as movable in the vertical opening 46 and adapted to drop to its inoperative position under its own weight when the electro-magnet 49 is de-energized, thereby omitting the spring 48, shown in Figure 8. 105

In both of these devices, however, the centering studs 47 are provided with pendant armatures or plungers 50, each of which, together with its corresponding electro-magnet 49, constitutes a solenoid. 110

In Figure 8 the plunger 50 and its center stud 47 is arranged to be drawn downwardly by the energizing of the magnet 49 for withdrawing the stud from its operative position, but in Figure 10 the plunger is arranged to be drawn upwardly by the energizing of its electro-magnet 49 for moving the center stud to its operative position during the operation of stacking the bowling pins upon the platform 8, thereby assuring the proper position of said pins ready for the player. In both modifications shown in Figures 8 and 10 the windings of the electro-magnets will be connected, preferably in parallel, in an operating circuit 51 deriving current from a suitable source of electric energy such as a battery B, Fig. 9, said circuit being provided with an electric switch 52 normally opened 120

by a spring 53, but adapted to be closed at the will of the operator for simultaneously energizing all of the magnets 49.

The movable member of the switch 52 is preferably mounted upon one side, in this instance the left hand side of the frame 3 closely adjacent the platform 8 where it may be operated by hand or by the knee of the player when restacking the bowling pins.

10 Operation

Assuming that the bowling pins *b* are stacked upon the platform 12, then the player standing upon the floor adjacent the platform 15 8 and storage shelf 12 will first close the switch 52 by hand or by the knee to raise all of the central plungers 47 which will be held in their raised positions as long as the switch 52 is closed and during which the bowling pins *b* will be taken from the shelf 12 and placed upon the platform 8 with the pins 47 engaged in the sockets *b'* of the corresponding bowling pins.

When the bowling pins are properly set the switch 52 is allowed to open by the action of its retracting spring 53 thus permitting the centering studs 47 to drop below the upper surface of the platform 8.

With the ball in hand the player then takes 30 his position upon the stand 10 with one foot upon the portion 6' and after visually selecting a point in the distal deflector block 4 to which the ball is to be directed to make the proper play, throws the ball across the intervening space between the stand 6' and upper runway 1 to cause the ball to travel along said runway to the distal end thereof where it is deflected downwardly and forwardly by the deflecting surface 5 on to the rear end 40 of the lower runway 2.

The impeller drum 14 being rotated in the direction indicated by arrow X will then engage the upper face of the ball and roll the same forwardly along the runway 2 with sufficient force to cause it to return upwardly and forwardly along the proximal deflector surface 7 and on to the platform 8 for displacing the bowling pins, thus completing one play which may be repeated until all of 50 the pins are displaced.

It will be observed that the axis of rotation of the drum 14 is carefully placed at right angles to the center lines of both runways 1 and 2 so that when the ball is directed along the upper runway to any particular point of the distal deflector block 4 it will engage the underside of the drum 14 at a point in substantially the same vertical plane as that selected by the player on the 55 deflector block 4, thus causing the impeller drum 14 to impel the ball along the lower runway and upon the pin-supporting platform 8 in the same longitudinal vertical plane previously selected.

60 In this manner the accuracy of the play

will depend entirely upon the accuracy of throw of the ball to the point selected in the distal deflector block.

It is also evident that the player may stack and restack the bowling pins from the stands 10 and 6', thereby dispensing with the services of a pin-boy and correspondingly reducing the dangers incidental to the operation of the displaced bowling pins.

70 Thus, the playing of the ball along the upper runway and the action of the ball upon the bowling pins are visible to the player from a playing position, and owing to the fact that the returned exposed balls and displaced pins always move rearwardly away from the player, reduces to a minimum the danger incidental to such operations.

75 It is evident, however, that some changes may be made in the construction of the apparatus without departing from the spirit of 80 this invention.

What I claim is:—

1. In a bowling alley, an outgoing runway and an underlying return runway, means for deflecting the ball from the distal end of the upper runway onto the adjacent end of the lower runway, and a rotary impeller arranged to engage the upper face of the downwardly deflected ball for impelling said ball along the return runway.

90 2. In a bowling alley, an outgoing runway and an underlying return runway, means for deflecting the ball from the distal end of the upper runway onto the adjacent end of the lower runway, and a rotary impeller arranged to engage the upper face of the downwardly deflected ball for impelling said ball along the return runway, and means for supporting the impeller independently of both 100 runways.

105 3. In a bowling alley, an outgoing runway and an underlying return runway, means for deflecting the ball from the distal end of the upper runway onto the adjacent end of the lower runway, and a rotary impeller arranged to engage the upper face of the downwardly deflected ball for impelling said ball along the return runway, said impeller being spring-pressed downwardly to cause it to frictionally engage the ball and to permit it to move upwardly by the ball as the latter passes between the impeller and lower runway.

110 4. A bowling alley composed of sections arranged end to end, and releasable means for holding said sections in operative relation, said alley having an outgoing upper runway and an underlying return runway, means at the distal end of the upper runway for deflecting the ball therefrom onto the lower runway, a pin supporting platform at the proximal end of the upper runway, and means for deflecting the ball from the proximal end of the lower runway onto said platform for displacing the pins.

115 5. In a bowling alley, a runway for the 120

balls, and a power-driven rotary impeller for frictionally engaging the upper side of the balls and propelling the same along said runway.

5 6. In a bowling alley, a runway for the balls, and a power-driven rotary impeller for frictionally engaging the upper side of the balls and propelling the same along said runway, and means for supporting said impeller independently of the runway to reduce the liability of transmission of vibration of said impeller to the runway.

10 In witness whereof I have hereunto set my hand this 5th day of June 1931.
